CLAIM

The ornamental design for a cooking pan, as shown and described.

DESCRIPTION

FIG. 1 is a front perspective view of a cooking pan showing the new design;

FIG. 2 is a right side view of the cooking pan of FIG. 1.

FIG. 3 is a left side view of the cooking pan of FIG. 1.

FIG. 4 is a front view of the cooking pan of FIG. 1.

FIG. 5 is a rear view of the cooking pan of FIG. 1.

FIG. 6 is a top view of the cooking pan of FIG. 1.

FIG. 7 is a bottom view of the cooking pan of FIG. 1.

FIG. 8 is a top perspective view of the cooking pan of FIG. 1; and,

FIG. 9 is a bottom perspective view of the cooking pan of FIG. 1.

The broken line showings are included for the purpose of illustrating portions of the invention and form no part of the claimed design.

1 Claim, 9 Drawing Sheets
